2 SHEETS—SHEET 2.

UNITED STATES PATENT OFFICE.

ADDISON W. BROCK, OF BALTIMORE, MARYLAND, ASSIGNOR TO H. GAMSE & BRO., OF BALTIMORE, MARYLAND.

BRONZING-MACHINE.

1,377,056.

Specification of Letters Patent.

Patented May 3, 1921.

Application filed July 1, 1920. Serial No. 393,341.

To all whom it may concern:

Be it known that I, ADDISON W. BROCK, a citizen of the United States, and resident of Baltimore, State of Maryland, have invented certain new and useful Improvements in Bronzing-Machines, of which the following is a specification.

This specification is in part a division of that of Letters Patent of the United States 10 #1,354,018, granted Sept. 28, 1920, including, however, in addition to features disclosed in that application, also features of improvement thereupon as will be particularly defined by the appended claims.

15 In the accompanying drawings:

Figure 1 is a side elevation of a bronzing machine and a portion of the offset press;

Fig. 2 is a plan view of the bronzing machine and a small portion of the offset press; 20 Fig. 3 is a detail side elevation of the means for operating the polishing rolls longitudinally;

Fig. 4 is a cross sectional view through the frame showing one of the polishing roll- 25 ers and the means for operating the same.

Like in the bronzing machine disclosed in the specification above referred to, the present machine includes carrier chains 14 passing around sprocket wheels 14^a and 14^b, and 30 these sprocket chains carry bridge bars 27 extending transversely over the machine from one chain to the other, as indicated in Fig. 4. These bridge bars support a blanket or apron 28 of flexible material, the bridge 35 bars forming a support for this belt so that sheets of paper carried by the belt and intended to be bronzed will be furnished a firm support so that the bronzing operation can be performed thereon.

40 The carrier chains are driven in unison with the delivery chains 1 of the offset press. These chains 1 pass around suitable sprockets, one at each side of the machine, and these sprockets are mounted on a shaft 45 21^x.

Motion is communicated from the shaft 21^x of the offset press to the shaft 17 of the bronzing machine, which carries the sprocket wheels of the chains 14, and this communication of power is effected through 50 the gears 24 and 25 in Fig. 2 at one side of the machine. Similar gears are arranged at the other side of the machine, but in Fig. 2, only a portion of the gear 25 is shown, because the view is broken away at this 55 point. The delivery chains of the offset

press carry grips 4 and there are grips 10 associated with the carrier mechanism of the bronzing machine, which as above indicated, includes the sprockets and chains 14, the bridge bars 27 and the blanket 28. The 60 grips of the offset press and the bronzing machine are operated in any suitable manner so that the sheet of paper after being printed is delivered by the operation of the 65 grips from the delivery chains of the offset press to the carrier means of the bronzing machine.

The mechanism for operating the grips may be of any suitable kind, for instance, like that disclosed in the above referred to 70 patent, and need not be particularly described herein.

The sheet when taken by the carrier means of the bronzing machine is carried 75 upwardly and follows the upper stretch of the carrier, the sheet resting on the blanket which is firmly supported by the bridge bars. The sheet is thus carried beneath a roll 26 in a hopper 31 which contains the bronzing material. This roll is operated 80 intermittently by a pawl and ratchet, 34 and 35, Fig. 2, the pawl being carried by an arm 36 and there being a suitable cam for operating this arm, to which motion is communicated through the gearing 41, 42. At 85 each partial rotation of the roll 26 the proper quantity of bronze is delivered from the hopper 31 onto the paper as this is carried beneath the roll. After leaving this roll the paper sheet with the bronze thereon 90 is carried beneath reciprocating bars 47 carried by rods 43, suitably guided in the frame parts so that the rods may be reciprocated longitudinally. The parts 47 are 95 representative of any suitable rubbing means which will rub down the bronze, for instance, the part 47 may be a plate carrying a sheet or strip of plush. The rubber bars are reciprocated by pitmen 52 operated by cranks 53 on a shaft 54, to which motion 100 is imparted through a sprocket chain 56, from shaft 57, driven by a belt-wheel 58.

After leaving the rubbing down bars the sheet of paper is carried beneath polishing rolls 59. These rolls are carried by shafts 105 60, which are adapted to be reciprocated in end bars 60^a. These rolls are covered with plush indicated at ^a, and they are rotated by a belt 62, passing over the pulleys 63 and around an idler pulley 64, the belt 110

being driven from a pulley 64^a on a shaft 64' which is driven through gearing 65—66 from the shaft 57. The reciprocating movement is imparted to the shafts 60 by levers 6, pivoted at c and driven from eccentrics 9, mounted on a shaft e, said shaft being driven through bevel gear f, g from the shaft 64' above mentioned. The pulleys 63 are held in position against axial 5
10 placement while allowing the shafts 60 to move axially, by a holding grip or bracket h, extending from the frame into a grooved collar i, on the side face of the pulley. The pulley is splined to the shafts 60 at k. Any 15 suitable means may be employed for adjusting the bearings of the shafts 60, vertically, such as indicated at 67 in Fig. 4. It will be seen from the above that the polishing rolls have not only a rotary movement but 20 a reciprocating movement so that the action of these rolls upon the bronze covered surfaces is similar to what may be termed a draw-cut action and this is more effective in securing an even polishing action on the 25 bronze covered surfaces than would be the case were the rolls simply rotated and not reciprocated. This roll having longitudinal and rotary movement simultaneously, will eliminate all streaky effects in the polishing 30 action and secure uniformity of work throughout the whole surface acted upon. Any suitable number of these reciprocating rotary polishing rolls may be employed and the present organization has three of these 35 as shown in Fig. 2. They work out of time with each other and, as shown in Fig. 2, the roll at the left of the series is at the limit of its stroke in one direction while the roll at the opposite end of the series is at 40 the limit of its reciprocating stroke in the opposite direction, while the intermediate roll is midway of its lengthwise stroke. After passing these reciprocating rolls the paper sheet is carried by a fourth roll, 59^a, 45 Fig. 2, which has no reciprocating movement axially and which completes the polishing action.

After leaving the polishing rolls the sheet is carried onward until it is taken by delivery means which include the chains 50 driven by any suitable gearing, from the carrier mechanism of the bronzing machine. This delivery mechanism will have grips which will receive the sheets from the grips 55 of the bronzing machine carrier and the sheets will finally be stacked on a jogger board, as in ordinary practice.

The bronzing machine is mounted upon 60 rolls or caster wheels A which are carried by supports or brackets B, suitably swiveled to supporting brackets C. There are a pair of caster wheels at the four corners of the frame, so that the bronzing machine readily 65 can be shifted in the establishment from one point to another, so that it may be lined up

with the delivery end of any one of a set of offset presses, and it will be understood that the same act of locating the bronzing machine in proper position relative to the offset press will have the effect of coupling the 70 carrier mechanism of the bronzing machine with the delivery mechanism of the offset press, so that this carrier mechanism will be operated in perfect unison with the delivery means of the offset press. This coupling action consists in bringing the gears 24, 25 into proper mesh. When the bronzing machine has been placed in proper position the coupling effect is completed by placing the 75 links 15 in connection with the ends of the 80 shafts 17 and 21^a so that the bronzing machine will be maintained in the position in which it is set and to aid in this effect, suitable supporting means are provided to slightly raise the bronzing machine frame 85 so that the caster wheels will no longer form the main supporting means but rigid or non-rolling elements will furnish fixed supporting means for the bronzing machine frame. These fixed or non-rolling supporting means 90 may assume various forms, but in the particular construction shown they consist of screws D threaded through suitable ears on the frame and bearing either upon the floor or upon plates E placed on the floor, there 95 being a set of four of these plates at each of the various positions on the floor of the establishment, to which the bronzing machine may be moved.

I claim as my invention:

1. A portable bronzing attachment for printing presses, comprising a frame resting on and shiftable from place to place upon the floor, an endless carrier, a shaft mounted in said frame, sprocket wheels on said shaft 105 and about which the endless carrier passes, a gear on said shaft, said endless carrier having grippers to take the printed sheets from the delivery means of the press, said attachment having bronze applying means to 110 apply bronze to the paper sheets as transported by the said carrier, said gear adapted to mesh with a gear connected with the delivery means of the printing press when the attachment is shifted in the prescribed relation to the press.

2. In connection with the features of claim 1, including the driving means consisting of the terminal gear, means for detachably connecting the bronzing attachment with the press, consisting of links mounted on and connecting the shafts of the gears.

3. A portable bronzing attachment for printing presses comprising carrier means 125 with grippers to take printed sheets from the delivery means of the press, bronze applying means, a supporting frame constituting with said carrier means and bronze applying means a bronzing unit to be moved from one 130

press to another, and means for connecting the said carrier means of the bronzing unit with the delivery means of the press to run in unison therewith, said connecting means being automatically set in effective position to transmit power from the press to the bronzing unit by the act of positioning the bronzing unit in proper relation to the press, substantially as described.

10 4. In combination, in a bronzing machine,

a frame, a carrier having grippers to transport the sheets to be bronzed, means for supplying bronze to the sheets and a plurality of polishing rolls with means for rotating them, and means for reciprocating each roll 15 axially and out of time with the other, substantially as described.

In testimony whereof I affix my signature.

ADDISON W. BROCK.
